[57] CLAIM

The ornamental design for a drinking cup, as shown and described.

DESCRIPTION

FIG. 1 is a perspective view from the bottom of the drinking cup according to this invention showing our new design therefor;

FIG. 2 is a top plan view of the drinking cup shown in FIG. 1;

FIG. 3 is a front elevational view thereof taken along line 3—3 of FIG. 2, the rear elevational view being a mirror image thereof;

FIG. 4 is a right side elevational view thereof taken along line 4—4 of FIG. 2, the left side elevational view being a mirror image thereof; and,

FIG. 5 is a bottom plan view of the drinking cup shown in FIG. 1.
